[57] CLAIM

The ornamental design for a toy truck, substantially as shown and described.

DESCRIPTION

FIG. 1 is a front perspective view of a toy truck showing my new design;

FIG. 2 is a left side elevational view thereof, the side opposite being a mirror image;

FIG. 3 is a top plan view thereof;

FIG. 4 is a front elevational view thereof; and,
FIG. 5 is a rear elevational view thereof.

The unshown bottom aspect of the claimed design is substantially flat, plain and unornamented.
